(57) **CLAIM**

We claim the ornamental design for a charging station as, shown and described.

DESCRIPTION

FIG. 1 is an isometric view of a charging station in a first configuration.

FIG. 2 is a front view of the charging station in the first configuration.

FIG. 3 is a rear view of the charging station in the first configuration.

FIG. 4 is a side view of the charging station in the first configuration.

FIG. 5 is another side view of the charging station in the first configuration.

FIG. 6 is a plan view of the charging station in the first configuration.

FIG. 7 is a bottom view of the charging station in the first configuration.

FIG. 8 is an isometric view of the charging station in a second configuration.

FIG. 9 is a front view of the charging station in the second configuration.

FIG. 10 is a rear view of the charging station in the second configuration.

FIG. 11 is a side view of the charging station in the second configuration.

FIG. 12 is another side view of the charging station in the second configuration.

FIG. 13 is a top view of the charging station in the second configuration; and,

FIG. 14 is a bottom view of the charging station in the second configuration.

The broken lines in the drawings illustrate portions of the charging station that form no part of the claimed design.

1 Claim, 8 Drawing Sheets
